CLAIM

The ornamental design for a tube strip with caps as shown and described.

DESCRIPTION

FIG. 1 is a perspective view of an embodiment of a tube strip with caps of our new design.

FIG. 2 is a front side view of FIG. 1.

FIG. 3 is a back side view of FIG. 1.

FIG. 4 is a right side view of FIG. 1.

FIG. 5 is a left side view of FIG. 1.

FIG. 6 is a top view of FIG. 1; and,

FIG. 7 is a bottom view of FIG. 1.

The portions of the features depicted in broken lines are not part of the claimed design.
